UNITED STATES PATENT OFFICE.

ROBERT B. OTIS, OF GOLDEN, COLORADO.

INTERNAL-COMBUSTION ENGINE.

1,000,192.

Specification of Letters Patent. Patented Aug. 8, 1911.

Application filed June 5, 1909. Serial No. 500,348.

To all whom it may concern:

Be it known that I, ROBERT B. OTIS, a citizen of the United States, residing at Golden, county of Jefferson, State of Colorado, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines and consists in the improvements hereinafter described and pointed out in the claims.

In the accompanying drawings,—Figure 1 is a side elevation of a two-cylinder engine embodying my invention. Fig. 2 is an end elevation of the same. Fig. 3 is a central section. Fig. 4 is a plan view, parts being broken away to economize room. Fig. 5 is a section in the plane indicated by the line 5—5 Fig. 3. Fig. 6 is a section in the plane indicated by the line 6—6 Fig. 3.

A, A¹ are the working cylinders.

B, B¹ are cylinders of greater diameter than the cylinders A, A¹, axially in line with the latter and forming an enlarged extension thereof.

C is the main shaft of the engine.

D, D¹ are cranks set opposite each other on the shaft C.

E, E¹ are connecting rods pivoted at their lower ends to the cranks D, D¹ and at their upper ends to trunk pistons F, F¹, adapted to reciprocate in the cylinders A, A¹.

G, G¹ are pistons fitting respectively and adapted to reciprocate in the cylinders B, B¹. The pistons G, G¹ are integral with and form enlargements respectively of the pistons F, F¹. The pistons G, G¹ form annular pump chambers g, g¹ above them in the cylinders B, B¹ surrounding the pistons F, F¹.

H, H¹ are the exhaust ports through which the products of combustion are discharged from the cylinders A, A¹.

h is a chamber between the cylinders A, A¹ with which chamber the exhaust ports H, H¹ communicate.

H² is a pipe through which the products of combustion are discharged from the chamber h.

h¹, h² are plates bolted onto the cylinders

A, A¹ and forming, when secured in place, inclosing walls to the chamber h.

I, J are valves located at the top of the cylinders A, A¹ respectively and adapted to open inward.

K, K¹ are valve casings inclosing the valves I, J.

b, b¹ indicate upward extensions of the annular pump chambers g, and g¹.

L, L¹ are pipes for conveying a charge of explosive mixture from an annular pump chamber g to the valve casing K¹ or from the annular pump chamber g¹ to the valve casing K. These pipes communicate respectively with the extensions b, b¹ from said annular pump chambers. The casing K is provided with an aperture at one side, and with a flat machined bearing surface surrounding said aperture; the casing K¹ is constructed like K except that the aperture and machined surface is upon the other side. The extensions b, b¹ are located upon opposite sides of the engine and laterally beyond the position of the plates h¹, h², and there is a lateral opening leading from each of said extensions surrounded by a flat machined bearing surface. The pipes L, L¹ are provided with flanges at their ends adapted to fit and be secured against the flat machined bearing surfaces at the sides of the casings K and K¹, and such surfaces surrounding the lateral openings leading from the extensions b, b¹, and such pipes are bowed so as to extend over the plates h¹, h².

M, M¹ (Fig. 6) are intake ports adapted to draw their charge through an inlet pipe M² which may communicate with a carburetor, so as to supply an explosive mixture.

m, m¹ are ports by which a charge of explosive mixture is drawn into the annular chamber g, or g¹, on the down stroke of the piston G or G¹.

The operation of the above described device is as follows:—When the piston G descends, an explosive mixture is drawn into the annular pump chamber g through the inlet port M. Meanwhile the explosive mixture in the cylinder A¹ is being compressed above the piston F¹. Said compressed explosive mixture is now fired, its expansion driving the piston F¹ downward on its working stroke. The piston G meanwhile rises compressing the explosive mixture in the pump chamber g above it and forcing said mixture into the pipe L and valve case

K¹. When the piston F¹ arrives near the end of its working stroke, the exhaust port H¹ is uncovered and the products of combustion are discharged into the chamber h through said port. When the pressure has sufficiently fallen in the cylinder A¹, the pressure of the explosive mixture above the valve J overcomes the spring j, forcing the valve J away from its seat and rushing into 10 and filling the cylinder A¹, above the piston F¹ and displacing the products of combustion through the exhaust port H¹. During this operation, a charge of explosive mixture has been taken into the annular chamber g¹ 15 and when the piston F¹ has nearly completed its compression stroke, said mixture has been forced into the pipe L¹ and valve case K, and when the piston F uncovers the exhaust port H and the products of combustion have been 20 discharged into the chamber h, said explosive mixture rushes into the cylinder A above the piston F, filling its explosion chamber and displacing a further quantity of the products of combustion. During the re- 25 turn stroke, the charge is compressed in the cylinder A above the piston F, as above described with reference to the cylinder A¹, and at the upper end of the stroke of the piston F, the compressed charge is fixed and 30 forces the piston F downward on its working stroke.

The construction by which the two cylinders exhaust into an intermediate chamber closed in by plates h¹, h², and by which the 35 flanged pipes L, L¹ pass over said plates upon opposite sides of the engine and are conveniently secured in place upon the flat machined bearing surfaces by corresponding flat flanges at their ends, forms a convenient 40 and symmetrical construction, which may be easily and conveniently put together and in which the joints are accessible and easily made tight.

Claims:—

45 1. In an internal combustion engine, two cylinders arranged side by side, each of said cylinders having a larger and a smaller part axially in line with each other, a piston fitting and adapted to reciprocate in the smaller 50 part of each of said cylinders and extending into the larger part thereof, each of said pistons being provided with an enlargement forming a piston in said larger part, and an annular pump chamber above 55 said enlargement, the smaller parts of said cylinders being provided with exhaust ports open from adjacent sides thereof, said cylinders being provided with an intermediate exhaust chamber, said exhaust ports opening 60 into said chamber, said cylinders being provided with valve cases K, K¹ on their smaller

parts one of said valve cases having an opening upon one side and the other of said valve cases an opening upon the side opposite to the opening in the other of said valve cases, 65 bearing surfaces surrounding said openings, lateral openings from said annular pump chambers the opening from one of said pumps being upon one side of the engine and that from the other of said pumps upon the 70 other side, and located to the side of said exhaust chamber, bearing surfaces around said openings, and pipes provided with flanges at their ends, fitted against said bearing surfaces and extending across said exhaust 75 chamber at opposite sides of the cylinders, said pipes connecting the pump chamber of each cylinder with the valve case of the other cylinder.

2. In an internal combustion engine, two 80 cylinders arranged side by side, each of said cylinders having a larger and a smaller part axially in line with each other, a piston fitting and adapted to reciprocate in the smaller 85 part of each of said cylinders and extending into the large part thereof, each of said pistons being provided with an enlargement forming a piston in said larger part, and an annular pump chamber above said enlargement, the smaller parts of said cylinders being 90 provided with exhaust ports open from adjacent sides thereof, said cylinders being provided with an intermediate exhaust chamber, said exhaust ports opening into said chamber, said cylinders being provided with 95 valve cases K, K¹ on their smaller parts, one of said valve cases having an opening upon one side and the other of said valve cases an opening upon the side opposite to the opening in the other of said valve cases, bearing 100 surfaces surrounding said openings, upward extensions to said annular chambers one of said extensions being upon one side of said engine and the other of said extensions upon the other side of said engine and located to 105 the side of said exhaust chamber, said upward extensions being provided with openings, bearing surfaces around said openings, and pipes L, L¹ provided with flanges at 110 their ends fitted against said bearing surfaces and extending across said exhaust chamber at opposite sides of the cylinders, said pipes connecting the pump chamber of each cylinder with the valve case of the other cylinder.

In testimony whereof, I sign this specification in the presence of two witnesses.

ROBERT B. OTIS.
